D. H. FRANCIS

SHALE RETORT

Filed May 2, 1921

Attorneys

Patented July 29, 1924.

UNITED STATES PATENT OFFICE.

DANIEL H. FRANCIS, OF GRAND JUNCTION, COLORADO.

SHALE RETORT.

Application filed May 2, 1921. Serial No. 466,102.

To all whom it may concern:

Be it known that I, DANIEL H. FRANCIS, a citizen of the United States of America, residing at Grand Junction, in the county of Mesa and State of Colorado, have invented certain new and useful Improvements in Shale Retorts, of which the following is a specification, reference being had therein to the accompanying drawings.

This invention relates to a shale retort, and the primary object of my invention is to provide a novel apparatus for heating or roasting shale or other ore to extract in vapor or gaseous form certain products retained by the shale or ore. As an example of the ore which may be treated in my retort I consider the oil bearing shale found in the southwestern part of the United States of sufficient value to warrant extracting the oil therefrom, and this is accomplished by placing the shale in my retort and subjecting it to heat which will liberate the oil as a vapor or gas that may be suitably condensed to obtain liquid oil.

Another object of my invention is to provide a simple and compact form of roasting apparatus on which ore may be distributed and heated. The design of the apparatus permits of the ore being preheated and the spent shale automatically removed from the apparatus.

The above and other objects are attained by a construction that will be hereinafter described and then claimed, and reference will now be had to the drawing, wherein

Figure 1 is a vertical sectional view of the shale retort, and

Fig. 2 is a horizontal sectional view on the line II—II of Fig. 1.

In the drawing, the reference numeral 1 denotes, by the way of an example, a furnace or heater having a combustion chamber 2 provided with a horizontally disposed top wall which affords a shale bed or roasting pan 3. A fire maintained in the combustion chamber 2 heats the shale bed 3 and said combustion chamber has a central exhaust flue or stack 4.

Suitably secured to the outer edges of the shale bed 3 is a conical dome or retort cover 5 and extending into the top of the dome 5 is the depending discharge end 6 of a hopper 7, said hopper surrounding the exhaust flue 4 so that shale deposited in the hopper 7 will encounter the walls of the exhaust flue

4 and be heated thereby before being discharged on to the shale bed 3.

Rotatable above the shale bed 3, in a horizontal plane, is a shale distributor, comprising a rim or circular rack 8, a hub portion 9 about the exhaust flue 4, and tangentially disposed or curved distributing spokes 10 connecting the hub 9 and the rim 8. Some of the spokes 10 are provided with adjustable scrapers 11 adapted to bear on the shale bed 3 and prevent shale from adhering thereto. To remove shale from the spokes 10, I provide a spring pressed scraper arm 19 which is pivoted in an offset portion 21 of the dome 5 and extends over the spokes with a depending end 22 bearing against a spoke. The upper edge of each spoke is notched, as at 23, so that after each scraping operation of the arm 19 it may automatically swing to adjacent spokes by the depending end 22 passing through the notches of the spokes.

Supporting the rotary shale distributor relative to the shale bed 3 are anti-frictional bearings which may be in the form of rollers, or wheels 12 in pockets 13 provided therefor by the shale bed 3, said antifrictional bearings supporting the rim or rack 8 of the distributor.

Adjacent the outer edges of the shale bed 3 are openings 14 communicating with the discharge spouts 15 supported by the walls of the furnace or heater 1. The discharge spouts are in the form of wells containing water which seals the retort against the admission of air, and such spent shale deposited in the water is removed by suitably operated screw propellers or conveyors.

Meshing with the rack 8 of the distributor is a pinion 16 carried by a shaft 17, and this shaft may be conveniently supported from the shale bed 3 and the dome 5 of the retort. Any suitable power may be employed for driving the shaft 17 so that the distributor will be revolved above the shale bed 3 to distribute shale deposited on the bed.

The top of the dome 5 is provided with a flue or conduit 18 adapted to extend to a condenser (not shown).

In operation, shale deposited in the hopper 7 passes downwardly through the discharge end 6 of the hopper and by contacting with the walls of the exhaust flue 4, the shale is somewhat heated before be-

ing deposited centrally of the shale bed 3. Quantities of the shale will be fed between the distributing spokes 10 of the rotary distributor and said spokes will cause the shale to be disseminated on the shale bed, whereby it will be heated and roasted sufficiently to liberate, as a vapor, such oil as may be contained within the shale. With the rotary distributor slowly revolving there is sufficient time for the shale to be heated and the oil liberated before the shale reaches the marginal edges of the shale bed, and spent shale will be carried to the openings 14 and discharged through the discharge 15 spouts. It is therefore possible to continuously carry on the operation of extracting oil from the shale, and since the retort may be operated at a comparatively small cost, the oil recovered by the retort is sufficient to warrant its use where the percentage of oil is low in shale.

As set forth in the beginning, the furnace 2 simply represents a conventional form of heater for the shale bed and it is obvious that oil burners, electric heating elements and the like may be substituted for the furnace. It is also to be understood that the structural elements entering into the

retort may be varied or changed without departing from the scope of the appended 30 claims.

What I claim is:—

1. A shale retort comprising an enclosed heated shale receiving bed, means for depositing shale centrally of said bed, a large 35 horizontally disposed wheel above said receiving bed and having spokes of a configuration to cause shale to be distributed from the central portion of said bed to the marginal portion thereof, and means 40 adapted to successively scrape the spokes of said wheel.

2. A shale retort comprising an enclosed heated shale receiving bed, spokes for distributing shale on said bed, and a scraping 45 arm adapted to swing from one spoke to another spoke, said spokes being notched to afford clearance for said arm when shifting from one spoke to another.

In testimony whereof I affix my signature 50 in presence of two witnesses.

DANIEL H. FRANCIS.
